UNITED STATES PATENT OFFICE.

PAUL A. GEHRING, OF KENOSHA, WISCONSIN.

TONGUE-HOUNDS.

No. 918,035.

Specification of Letters Patent.

Patented April 13, 1909.

Application filed May 9, 1908. Serial No. 431,905.

To all whom it may concern:

Be it known that I, PAUL A. GEHRING, a citizen of the United States, residing at Kenosha, county of Kenosha, and State of 5 Wisconsin, have invented certain new and useful Improvements in Tongue-Hounds, of which the following is a specification.

My invention relates to the tongue-hounds of wagons, that is, to the device for securing 10 the tongue to the wagon-hounds.

The object of my invention is to provide an adjustable device of the class mentioned, by means of which the tongue may be secured to the hounds of any wagon. In 15 wagons of different sizes or makes, the wagon-hounds are fixed at various angles, and the tongue-hounds which are secured thereto must be parallel therewith.

Heretofore, so far as I am aware, the 20 tongue-hounds are made in one piece or are arranged in fixed relation to each other, in which case, they are adapted to be secured to such wagons only in which the wagon-hounds are at substantially the same angle 25 as said tongue-hounds and at the same distance apart. By equipping a wagon-tongue with adjustable hounds, the same may be secured or attached to the hounds of practically any wagon.

30 Other objects will appear hereinafter.

My invention will be more readily understood by reference to the accompanying drawings forming a part of this specification, and in which,

35 Figure 1 is a plan view of a device embodying my invention in its preferred form, illustrating the same secured to the wagon-hounds, Fig. 2 is a similar view of the device detached, and illustrating the same in different adjusted positions, Fig. 3 is a section on the line $x-x$ of Fig. 2, Fig. 4 is a longitudinal section on the line $y-y$ of Fig. 2, Fig. 5 is a transverse section on the line $z-z$ of the same figure, Fig. 6 is a detail view of one of the adjustable blocks in which the main bolt is arranged, Fig. 7 is a plan view of a modified form of my invention, illustrated upon a reduced scale, and Fig. 8 is a similar view of a further modification.

50 Referring now to the drawings 1—1 indicate the wagon-hounds, and 2 the truck bolster of an ordinary wagon, and 3 indicates a wagon-pole or tongue secured thereto by the adjustable device embodying my invention.

55 4 indicates the tongue-socket to receive the butt end of the tongue which is secured

therein by the bolts 5. The tongue socket comprises a top plate portion 6 and the substantially parallel side walls 7, which latter may be slightly tapered or convergent at 60 their inner ends as indicated at 8. The bolts 5 pass through the side walls 7 which are provided with the bolt holes 9 to receive them.

10—10 indicate the tongue-hounds proper, 65 which consist of straight channel members comprising the vertical outer side walls 11 which lie against the inner face of the wagon-hounds 1, and the inwardly extending top and bottom flanges 12 and 13. The members 10 are adjustably connected to the tongue-socket and suitable means are provided for adjusting them and holding them in adjusted position. To this end, the forward ends of the members 10 are hingedly 70 connected as at 14, to the links 15, the latter of which are preferably curved, and which are in turn, hingedly connected at their forward ends as at 16 to plates or members 17, adjustably connected or mounted upon the 75 side walls 7 of the socket. The members 17 are secured in position by the bolts 5, said members being slotted as at 18 to receive said bolts and to permit longitudinal adjustment of said members on the socket portion. 80 To insure said members against slipping after having been adjusted, a portion of their inner faces is corrugated as at 19, and the adjacent portions of the walls 7 are also preferably correspondingly corrugated as at 20. 90

21—21 indicate a pair of sleeves pivotally mounted at their inner ends between the flanges 12 and 13 of the members 10 at or near their forward ends. The sleeves 21 are internally threaded and are connected by a 95 bolt or threaded rod 23, the opposite ends of which are threaded into the sleeves, one end being provided with right hand threads and the other end with left hand threads. Pivotally connected to the members 10 as at 24 near their rear ends, is a pair of similar sleeves 25 connected by a bolt or rod 26 which is also oppositely threaded into the sleeves 25.

It is obvious that by turning the rods 23 105 and 26, the members 10 may be adjusted to any desired angle and at any desired distance apart to fit snugly against the wagon-hounds 1. Suitable means must be provided for maintaining the members 10 at equal distances and at equal angles upon each side of the axis of the tongue. To this end, the 110

tongue socket is provided with an extension which comprises a tapered plate or horizontal flange 27 forming a continuation of the plate 6 and a central depending flange 28 forming a substantially T shaped member. Formed upon the under face of the member 27 is a pair of parallel lugs or ears 29 through which the rod 23 passes and said rod is provided with a squared collar 30 arranged 10 between said lugs. This forms a wrench hold by means of which the rod is turned, and also maintains the forward ends of the members 10 at equal distances each side of the tongue. The member 27 is also provided 15 with a pair of similar ears or lugs 31 between which is arranged a squared collar 32 formed on the rod 26, and which serves the same purpose as the collar 30 before mentioned.

33 indicates the main bolt by means of 20 which, the tongue and tongue-hounds are pivotally secured to the wagon-hounds 1. This is mounted in draft-blocks 34-34 secured to the inner face of the walls 11 of the tongue-hound, said blocks being provided 25 with the substantially central holes 35 to receive the bolt. The blocks are adjustably mounted within the members 10 and the walls 11 are slotted as at 36 to permit longitudinal adjustment thereof. To prevent 30 slippage of the blocks after having been adjusted, their lower edges are provided with a corrugated or serrated portion 37, and the adjacent upper face of the flange 13 is correspondingly corrugated as at 38. The blocks 35 fit snugly between the walls 12 and 13, and must be removed from between said walls or flanges to adjust their position. The blocks are readily replaced in proper position, the corrugations thereon entering the corrugations in the flange 13. After the blocks are 40 adjusted, pairs of bolts passing vertically through the flanges 12 and 13 hold them in place, 39 indicating the bolts.

In Fig. 7 I have shown a modification 45 wherein the sleeves 21 and 25 and their respective rods or bolts 23 and 26, are replaced by the bars 40 pivotally connected to the members 10. These are provided with notched or corrugated faces 41 which engage 50 correspondingly corrugated faces 42 on blocks 43 fixed to the extension 27. The bars 40 are held in engagement with the blocks 43 by the bolts 44 and the bars are slotted as at 45 to receive said bolts and permit adjustment of the device.

In the modification shown in Fig. 8 a pair of lever arms 46 are pivotally connected as at 47 to the members 10 and their opposite ends are pivotally connected as at 48 to 60 blocks 49 slidably or adjustably mounted on the extension 27' of the tongue-socket. A bolt 50 passing through said blocks and a longitudinal slot 51 adjustably secures said blocks to said extension. A pair of similar 65 levers 52 are pivotally connected as at 53

to the rear ends of the members 10 and at their opposite ends to sliding blocks 54 similar to the blocks 49. The blocks are adjustably secured to the portion 27' by a bolt 55 extending therethrough and through 70 a slot 56 in said extension. It is obvious that by adjusting the position of the blocks on said extension, the position of the tongue-hounds 10 may be nicely adjusted.

Having described my invention what I 75 claim as new and desire to secure by Letters Patent, is:

1. In a device of the class described, the tongue socket in combination with the tongue hounds hinged links connecting said 80 socket and said hounds, sleeves pivotally connected to said hounds, threaded rods interposed between said sleeves upon opposite hounds and threaded thereinto, and co-acting means on said tongue socket and said 85 rods for maintaining said hounds at equal distances each side of said socket, substantially as described.

2. In a device of the class described, the tongue socket in combination with the 90 tongue hounds, hinged links connecting said socket and said hounds, means for adjusting the forward ends of said hounds toward and from each other, similar means for adjusting the rear ends of the hounds and draft blocks 95 adjustably mounted on said hounds, substantially as described.

3. In a device of the class described, the tongue socket in combination with the tongue hounds, hinged links connecting said 100 socket and said hounds, said hounds being longitudinally slotted, draft blocks adjustably secured to said hounds, and the main bolt extending through said slotted hounds and having bearings in said blocks, substantially as described.

4. In a device of the class described, the tongue socket in combination with the tongue hounds, said hounds comprising channel members with their flanges extending 110 horizontally inward, hinged links connecting said socket and said hounds, means for adjusting said hounds, the vertical walls of said channels being longitudinally slotted and one of said horizontal flanges being 115 transversely corrugated adjacent the slots, draft blocks arranged between said horizontal flanges and provided with a corrugated edge adapted to engage the corrugated portion of the flange and a main bolt mounted in 120 said blocks, substantially as described.

5. In a device of the class described, the tongue socket in combination with the tongue hounds, said hounds comprising channel members having vertical webs and 125 interturned horizontal flanges, said webs being provided with longitudinal slots, draft blocks fitting snugly between said flanges, one of said flanges being transversely corrugated and the adjacent edge of said block being 130

correspondingly corrugated to prevent longitudinal movement of the blocks on said hounds, and bolts extending through said flanges in front of said blocks to prevent lateral movement of the same and to detachably secure said blocks within said channel members, substantially as described.

In testimony whereof I have signed my name to this specification in the presence of two subscribing witnesses.

PAUL A. GEHRING.
